UNITED STATES PATENT OFFICE.

CHRISTIAN ALTER, OF NEW YORK, N. Y.

RAZOR-BLADE SHARPENER.

1,060,657.

Specification of Letters Patent.

Patented May 6, 1913.

Application filed February 16, 1912. Serial No. 677,901.

To all whom it may concern:

Be it known that I, CHRISTIAN ALTER, a citizen of the United States, and a resident of the city of New York, borough of Manhattan, in the county and State of New York, have invented a new and Improved Razor-Blade Sharpener, of which the following is a full, clear, and exact description.

The invention relates to razor stropping and honing machines, such as shown and described in the Letters Patent of the United States, No. 1,001,573, granted to me on August 22, 1911.

The object of the present invention is to provide a new and improved razor blade sharpener, which is simple and durable in construction, easily manipulated and arranged to permit convenient and quick sharpening of the ordinary razors or the blades of various makes of safety razors.

For the purpose mentioned use is made of a revolute sharpening wheel adapted to be engaged by the razor blade removably held in a holder mounted on a swing arm to move either side of the cutting edge of the blade into engagement with the peripheral face of the said wheel, the said swing arm and the said wheel being controlled by a reversible driving mechanism under the control of the operator.

A practical embodiment of the invention is represented in the accompanying drawings forming a part of this specification, in which similar characters of reference indicate corresponding parts in all the views.

Figure 1 is a side elevation of the razor blade sharpener arranged for holding it in the hand while using it; Fig. 2 is a front end elevation of the same; Fig. 3 is a sectional side elevation of the same clamped to a table or other support; Fig. 4 is a rear end elevation of the same with parts in a different position; Fig. 5 is a sectional plan view of the same on the line 5—5 of Fig. 1; Fig. 6 is a cross section of the sharpening wheel, the section being on the line 6—6 of Fig. 3; Fig. 7 is an enlarged cross section of the holder, the section being on the line 7—7 of Fig. 1, and the holder being arranged for holding flexible razor blades having a reinforced back or Gillette razor blades; and Fig. 8 is a cross section of a modified form of the holder arranged for holding non-flexible razor blades.

The razor blade sharpener is mounted on a suitably constructed frame A provided

with a handle B for holding the frame in the hand while using the razor blade sharpener, but if desired the frame A may be fastened by a suitable clamp C to a table D or other support, as plainly indicated in Fig. 3. The frame A is provided with a tubular bearing E in which is mounted to turn a shaft F, and on the said bearing E is mounted to turn a sleeve G carrying a sharpening wheel H provided with a peripheral face H' of leather for stropping purposes, or of stone or the like material for honing purposes. The wheel H is adapted to turn with the shaft F, and for this purpose the outer end of the shaft F is provided with a projection F' adapted to engage either side of a tooth or a projection G' formed on the outer end of the sleeve G so that when the shaft F is turned in one direction the projection F' engages one side of the tooth G' to rotate the wheel H in the same direction as the shaft, and when the shaft F is turned in an opposite direction then the wheel H remains at a standstill for the time being until the projection F' has swung around and engaged the other side of the tooth G' to thus turn the wheel G in the reverse direction, that is, in the direction in which the shaft is turning at the time.

The peripheral face of the wheel H is adapted to be engaged by either side of the cutting edge of the razor blade I to be sharpened, the said razor blade being removably mounted in a holder J adjustably secured on the outer member K' of a swing arm K having a pivoted member K² journaled in a bearing E' attached to or forming part of the frame A. The members K' and K² are preferably parallel to each other and parallel to the axis of the wheel H, and when the swing arm K is swung to one side, for instance, as shown in dotted lines in Fig. 2, then one side of the cutting edge of the blade I is moved into engagement with the peripheral face of the wheel H' and when the swing arm K' is swung over to the opposite side as indicated in Fig. 4 then the other side of the razor blade I is moved into contact with the peripheral face of the wheel H.

In order to swing the swing arm K into either of the two positions mentioned and to turn the wheel H in a corresponding direction, the following arrangement is made: The head L' of a crank arm L is mounted loosely on the bearing E' and is provided

with a gear wheel N in mesh with a gear wheel N' secured on the inner end of the shaft F . Thus when the crank arm L is turned around in one direction a rotary motion is given to the wheel H in the opposite direction, and when the crank arm L is turned in a reverse direction then the wheel H is likewise reversed. The crank arm L is connected by a friction device O with the journal member K^2 of the swing arm K , the said friction device O having two clamping members engaging opposite sides of a collar K^3 fixed on the outer end of the journal member K^2 , and the said clamping members are attached at one end at O' to the crank arm L , and a screw O^2 passes through the free end of one of the clamping members and screws in the free end of the other clamping members so as to engage the clamping members with more or less force as desired by the operator. By the use of the friction device O the swing arm K turns with the crank arm L so as to swing the swing arm K to either side, as previously mentioned and shown in Figs. 2 and 4, with a view to engage opposite sides of the razor blade I with the peripheral face of the sharpening wheel H , and when this has been done and a further turning is given by the operator to the crank arm L then the members of the friction device O glide over the collar K^3 and thus hold the cutting edge of the blade I with the desired force in contact with the peripheral face of the wheel H . It is understood that when the operator stops rotating the crank arm L in one direction and begins to swing the crank arm over in the opposite direction then the wheel H remains stationary for the time being until the projection F' passes around and engages the other side of the projection G' , as above explained, so that the cutting edge of the blade I is lifted off the peripheral face of the wheel H at the time the latter is at a standstill, and about the time the razor blade I and the holder J stands in vertical position the wheel H begins to rotate in the opposite direction and is rotating by the time the other side of the razor blade I engages the peripheral face of the wheel H . By the operator adjusting the clamping screw O^2 more or less friction is had between the clamping members and the collar K^3 , and consequently the razor blade is held with more or less force in contact with the peripheral face of the roller H . The handle L^2 of the crank arm L is preferably removable to permit of packing the parts in a comparatively small box.

As previously mentioned, the wheel H is removably held on the sleeve G to permit the interchange of wheels for stropping or honing purposes, and in order to lock the wheel H in place on the sleeve G so as to rotate with the latter and to prevent accidental re-

moval of the wheel from the sleeve the following arrangement is made: Near the inner end of the sleeve G is formed an outwardly-extending lug G^2 adapted to fit into a recess H^2 arranged on the inner end of the wheel H (see Fig. 3), so that when the sleeve G is turned the wheel H turns with it. The lug G^2 is adapted to be engaged by a locking arm P held on the inner end of a rod P' extending lengthwise through the wheel H , and being provided on its outer end with an angular handle P^2 under the control of the user. Thus after the wheel H has been slipped onto the sleeve G and the lug G^2 has engaged the recess H^2 then the operator swings the handle P^2 inward toward the center of the wheel so as to swing the arm P over the rear face of the lug G^2 to lock the wheel H against sliding off the sleeve G .

The blade holder J is arranged to accommodate razor blades of various makes of safety razors, and the holder J is preferably in the form of a clamp having a hollow back J' and clamping members J^2, J^3 between which passes the blade I with the reinforced back I' of the blade extending into the back J' of the holder, as plainly indicated in Figs. 3 and 7. The front member J^3 of the holder J is provided with spaced apertures J^4 through which extend clamping pins Q held on a clamping lever Q' fulcrumed at Q^2 on the front member J^3 , and the said clamping lever Q' is provided with a struck up tongue Q^3 bearing against the member J^3 to normally hold the clamping lugs or pins Q in engagement with the razor blade I , thus pressing the same against the holder member J^2 . The clamping lever Q' is provided with an upwardly-extending handle Q^4 under the control of the operator for conveniently pressing the clamping lever so as to move the lugs Q out of engagement with the blade I to allow removal thereof from the holder. In case the blade I is of the Gillette type, that is, provided with apertures then the said lugs Q of the clamping lever Q' engage the said apertures thus holding the blade securely in position in the holder J . For non-flexible razor blades, as shown in Fig. 8, the holder J has its back J' made in tubular form so as to readily accommodate the heavy back of such razor blade, but otherwise the blade is held clamped in position in the holder J by the lugs Q of the lever Q' .

In order to accommodate razor blades of more or less width it is necessary to adjust the holder J nearer to or farther from the peripheral face of the wheel H , and for this purpose the holder J is provided on top with a threaded shank J^5 screwing in a nut K^4 secured or formed on the free member K' of the swing arm K . The threaded shank J^5 is provided with a lengthwise-

extending groove J^6 (see Fig. 7) engaged by a set screw R screwing in the nut K^6 and serving to lock the shank J^6 and consequently the holder J in the adjusted position. The said screw R is of a diameter somewhat less than the width of the groove J^6 to allow a slight turning movement of the holder J to permit the cutting edge of the blade I to properly engage the peripheral face of the sharpening wheel H . The swing arm K is provided with a mark K^6 to permit proper adjustment of the holder J for blades I of more or less width, it being understood that the holder J with the blade I therein is adjusted until the cutting edge of the blade I registers with the mark K^6 , as will be readily understood by reference to Fig. 1, it being understood that when the holder J is so adjusted and the crank arm L is turned then the cutting edge of the blade I engages the peripheral face of the wheel H at the correct angle to insure proper sharpening of the cutting edge.

Having thus described my invention, I claim as new and desire to secure by Letters Patent:

1. A razor blade sharpener, comprising a revoluble sharpening wheel, a swing arm, a blade holder on the said swing arm for holding a razor blade in peripheral engagement with the said wheel, and actuating means frictionally connected with the said swing arm and positively connected with the said sharpening wheel to rotate the latter and to impart a swinging motion to the said swing arm to engage either side of the cutting edge of the blade with the peripheral face of the said wheel.

2. A razor blade sharpener, comprising a revoluble sharpening wheel, a swing arm having a member approximately parallel to the axis of the said wheel, a blade holder on the said swing arm member and adapted to hold a blade in engagement with the peripheral face of the said wheel, a manually-controlled gearing for rotating the said wheel, and a friction drive connected with the said gearing and mounted on the said swing arm to impart a swinging motion to the latter to engage either side of the cutting edge of the blade with the peripheral face of the said wheel.

3. A razor blade sharpener, comprising a revoluble sharpening wheel, a swing arm having a member approximately parallel to the axis of the said wheel, a blade holder on the said swing arm member and adapted to hold a blade in engagement with the peripheral face of the said wheel, a crank arm mounted to turn loosely on the pivot of the said swing arm, gear wheels connecting the said crank arm with the said wheel, and a friction device connecting the said crank arm with the pivot of the said swing arm.

4. A razor blade sharpener, comprising a

revoluble sharpening wheel, a swing arm having a member extending approximately parallel to the said wheel, a blade holder for holding a razor blade and adjustably held on the said swing arm member, and manually-controlled means for imparting a swinging motion to the said swing arm and rotating the said wheel.

5. A razor blade sharpener, comprising a frame, a shaft journaled in the said frame, a sleeve on the said shaft and adapted to turn with the said shaft, a sharpening wheel removably held on the said sleeve and rotating with the same, a swing arm having parallel members at the ends, one of the said members being the outer free member and parallel to the axis of the said wheel, and the other member being journaled in a bearing on the said frame, a blade holder on the said free member of the swing frame, a crank arm having a hub loose on the bearing for the journal member of the swing arm, gear wheels connecting the hub of the said crank arm with the said shaft, and a friction clamp held on the said crank arm and engaging the said journal member of the swing arm.

6. A razor blade sharpener, comprising a frame, a shaft journaled in the said frame, a sleeve on the said shaft and adapted to turn with the said shaft, the said sleeve having a projecting tooth at the outer end and the said shaft having a lug adapted to engage either side of the said tooth, a sharpening wheel removably held on the said sleeve and rotating with the same, a swing arm having parallel members at the ends, one of the said members being the outer free member and parallel to the axis of the said wheel, and the other member being journaled in a bearing on the said frame, a blade holder on the said free member of the swing frame, a crank arm having a hub loose on the bearing for the journal member of the swing arm, gear wheels connecting the hub of the said crank arm with the said shaft, and a friction clamp held on the said crank arm and engaging the said journal member of the swing arm.

7. A razor blade sharpener, comprising a frame, a shaft journaled in the said frame, a sleeve on the said shaft and adapted to turn with the said shaft, a sharpening wheel removably held on the said sleeve and rotating with the same, a swing arm having parallel members at the ends, one of the said members being the outer free member and parallel to the axis of the said wheel, and the other member being journaled in a bearing on the said frame, a blade holder on the said free member of the swing frame, a crank arm having a hub loose on the bearing for the journal member of the swing arm, gear wheels connecting the hub of the said crank arm with the said shaft, and a

friction clamp held on the said crank arm and engaging the said journal member of the swing arm.

8. A razor blade sharpener, comprising a 5 revolute sharpening wheel, a swing arm having a nut, a blade holder having a threaded shank screwing in the said nut to adjust the blade holder nearer to or farther from the peripheral face of the said wheel, 10 the said threaded shank having a groove extending lengthwise of the shank, and a set screw on the swing arm engaging the said groove.

9. A razor blade sharpener provided with 15 a sharpening wheel, a sleeve slidably engaged by the said wheel and having an upturned lug, and a locking rod extending through the said wheel and provided at its rear end with a locking arm adapted to en-

gage the said lug, the said locking rod having a handle on the forward end for turning the rod.

10. A razor blade sharpener, provided with a sharpening wheel having a recess at its rear end, a sleeve onto which fits the 25 said wheel and provided with a lug adapted to engage the said recess to rotate the wheel on turning the sleeve, and a manually-controlled locking device on the wheel engaging the said lug to hold the wheel against removal from the sleeve.

In testimony whereof I have signed my name to this specification in the presence of two subscribing witnesses.

CHRISTIAN ALTER.
